UNITED STATES PATENT OFFICE.

ABRAHAM BELLOW, OF LEEDS, ENGLAND.

CHAINSTITCH SEWING MACHINE.

Application filed February 6, 1923. Serial No. 617,289.

To all whom it may concern:

Be it known that I, ABRAHAM BELLOW, a subject of the King of Great Britain and Ireland, residing at Leeds, in the county of 5 York, England, have invented new and useful Improvements in or Relating to Chain-stitch Sewing Machines (for which I have filed application in Great Britain December 21, 1921), of which the following is a specification.

This invention relates to chain-stitch sewing machines and more particularly those known as padding, bridling and stay-felling machines, of the kind wherein that portion 15 of the goods through which the stitches are to pass is held at an angle to the body of the goods, to enable the needle, which is of the ordinary straight type, to get a bight therein, said needle being reciprocated transversely across the line of feed in a substantially horizontal plane to pierce the goods while held at such angle and entering and emerging on the same face of the fabric, a 20 loop-taking device co-operating with said needle to complete the formation of the stitch, and wherein the needle is adapted to be reciprocated in a stationary guide member forming part of or attached directly to the main frame of the machine.

According to the present invention the 30 needle travels in a plane substantially parallel to the axis of the main driving shaft and works in conjunction with a forked member, not novel, per se, for drawing out the loop. Thus the needle is adapted to slide to and fro in a suitable guide under the action of a bell-crank lever operated from the main driving shaft by means of 35 spur wheels suitably connected to one arm of said bell-crank lever, whilst to ensure of the necessary blind stitch being produced, the material is raised by means of a plunger, connected to and operated by one end of a lever, fulcrumed at or about its centre, its 40 opposite end being connected by a link member to an eccentric on the main driving shaft, to allow the needle to penetrate only to such a depth of the material as is necessary.

In order that the invention may be clearly 45 understood and readily carried into effect, the same will now be more fully described with reference to the accompanying sheets of drawings which illustrate my invention, Figure 1 being a side elevation of the machine, Figure 2 an elevation of the machine from the opposite side thereof to the illus-

tration in Figure 1, Figure 3 an elevation from the front, and Figure 4, a plan.

The needle 10 is adapted to be reciprocated to engage the material by means of a bell-crank lever 11 pivoted at 12 to an arm 13 extending from the body of the machine, one end of said lever 11 being suitably connected to the needle bar 14, which is adapted to securely hold the needle 10 by means of the screw 15 engaging the shank thereof, the needle bar 14 being supported in its turn from a further arm 16 of the machine, by a U-shaped guide 17, said guide being attached to the arm 16 in such a manner as to be capable of longitudinal adjustment at will. The other end of the bell-crank lever 11 is operated from the main driving shaft 18 through the intermediary of spur wheels 19, 20, and link 21, said link being attached to the end of the lever 11 by a ball joint 22, the other end of the link being attached to a pin 23 on the spur wheel 20, said pin 23 being positioned eccentrically to the centre of the wheel as is clearly shown. The looper fork 24, which takes up the loop formed by the retraction of the needle as is hereinafter described, is operated from the main driving shaft 18 by means comprising a disc 25 with a cranked extension 26 which carries a pin 27, said pin supporting the connecting piece 28 in such a manner as to allow of the latter moving freely around the pin 27. The connecting piece 28 is provided essentially with two adjacent bores or holes at right-angles to each other, one to receive the pin 27 by which it is supported, and the other to receive a further pin or the like 29 which supports the forked member 24. Positioned at a suitable point between the fork 24 and the fork 30 is a bearing of the universal type, 32, which is mounted to oscillate on a bracket or pin 33 screwed or otherwise secured to the body portion of the machine, under the action of the mechanism above described, said bearing 32 serving to support the active end of the looper bar 31, the arrangement, to which I make no claim, being of the usual type now generally fitted to padding machines of this type for drawing out the loop. To facilitate the blind-stitching of different thicknesses of material and also to regulate the amount of penetration of the needle into the material, i. e.—the distance the stitch is away from the face side of the cloth, a plunger is provided which is automatically operated to move or lift the

material into the exact position to produce the desired blind-stitch. This plunger mechanism comprises a pencil-like member 34 at the lower end of which, adjusting means are provided for connecting said plunger 34 to one end of a longitudinal rocking bar 36, the other end of which is connected by a link 37 to an eccentric 38 on the driving shaft 18. The adjusting means above referred to, may comprise a threaded member 39 provided with a handle 40 extending from the collar 41 on the shank thereof, said collar being suitably serrated to receive a spring-pawl-like member 42, the construction being such that when the handle 40 is moved in one direction the plunger 34 is raised a short distance whilst when moved in the opposite direction it is lowered, the operator knowing by the number of clicks caused by the pawl 42 taking within the serrations of the collar 41, how much to move the handle 40 to obtain a certain result. During the stitching of the material the latter is fed or moved forward under the action of a feeder 43 which works in a suitable guide member 44, said guide being supported from a projection or the like 45 of the body portion of the machine. The feeder 43 is carried by an angular presser bar 46, said presser bar being connected to an oscillating link member 47 fulcrumed towards the forward end of the machine, which link member is connected by the bar 48 to the strap of an eccentric 49 on the driving shaft 18, the arrangement being such that the feeder 43 will move the material forward a predetermined amount into the path of the needle 10, after which the feeder is raised to release the material and returns to its forward position when it is lowered to again perform its feeding operation, whilst to guide the material over the work plate 50, which is formed with a ridge or raised portion at 51 extending approximately the whole thereof to automatically impart to the material the desired rounded effect. A further eccentric 52 on the main shaft 18 is adapted to operate the lever 53 which slides to and fro about a pin 54 secured to the frame of the machine, the forward end of said lever 53 being provided with a suitable foot 55 for guiding the material, the combined action of foot just described and the feeder 43 tending to feed the material straight without any aid from the operator. The work plate 50 is supported by a multiplicity of spiral springs 56 from a box-like member 57 which is capable of sliding in a vertical plane in the foot 58, said box-like member being adjustably secured thereto by the bolts 59, springs 60 tending to keep it in its raised position, such position being regulated by the nuts 61 on the bolts 59, means in the form of a lever 62 being provided for lowering said

box 57 and its associated parts to release the material as and when required for removal from the machine.

For allowing of different thicknesses or kinds of material being worked or operated upon, the various parts may be made capable of adjustment as and when required.

In operation the needle 10 with its thread is caused to penetrate the cloth, which is positioned between the work plate 50 and the guide member or feed plate 44, in such a manner that the stitch formed does not show on the face thereof, the needle emerging from the cloth at the forward end of its stroke or travel on the same side or surface as it originally entered without in any way penetrating or emerging from the opposite side of the cloth, during its reciprocation, and further, the needle 10 is moved out on its forward stroke such a distance, that, upon its being retracted, the thread projecting from the material at that end of the stitch furthest away from that where the initial penetration took place, forms a loop, which is taken up by the looper fork 24 as the needle is retracted, said looper fork drawing out and positioning the loop so as to enable its being correctly taken up by the needle on its next forward movement. Thus the looper fork 24 engages the thread with both its prongs in a horizontal plane, which prongs turn into a vertical plane as the looper is performing its sideways movement across the feed plate 44, during which movement the needle is retracted from the material to allow the latter to be fed forward the required amount, after which the needle is again moved forward to pass between the crown of the looper prongs and the thread, which is still engaged thereby, but which is now disengaged by the needle, the latter continuing its forward movement to again penetrate the material, whilst the looper is withdrawn and returned to its initial position ready for taking up the next loop.

I claim:—

1. The combination with the body of a chain-stitch sewing machine, of a needle adapted to be reciprocated transversely across said body in a substantially horizontal plane, a drive shaft, spur wheels operatively associated with said shaft, a bell crank connected at one end to said needle and at its opposite extremity secured to one of said spur wheels, loop-taking mechanism co-operating with said needle and operatively connected to said driving shaft, a feeder, an oscillating link connecting said feeder to the drive shaft, a work plate over which said needle works, a box-like member below said plate, springs on said member resiliently supporting said plate, and means projecting from said member for raising or lowering the same.

2. The combination with the body of a chain-stitch sewing machine, of a needle adapted to be reciprocated transversely across said body in a substantially horizontal plane, a drive shaft, spur wheels operatively associated with said shaft, a bell crank connected at one end to said needle and at its opposite extremity secured to one of said spur wheels, loop-taking mechanism co-operating with said needle and operatively connected to said driving shaft, means for regulating the amount of penetration of the needle into the material, a feeder, an oscillating link connecting said feeder to the drive shaft, a work plate, a box-like member below said plate, springs on said member resiliently supporting said plate, and means projecting from said member for raising or lowering the same. 4. The combination with the body of a chain-stitch sewing machine, of a needle adapted to be reciprocated transversely across said body in a substantially horizontal plane, a drive shaft, spur wheels operatively associated with said shaft, a bell crank connected at one end to said needle and at its opposite extremity secured to one of said spur wheels, loop-taking mechanism co-operating with said needle and operatively connected to said driving shaft, means for manually regulating the amount of penetration of the needle into the material comprising a plunger, a rocking bar connected to one end of said plunger, and its opposite end secured to said drive shaft, manual means connected to said plunger for adjusting the latter, a feeder, an oscillating link connecting said feeder to the drive shaft, a work plate having a raised portion for automatically imparting to the material the desired curve, a box-like member below said plate, springs on said member resiliently supporting said plate, and means projecting from said member for raising or lowering the same. 3. The combination with the body of a chain-stitch sewing machine, of a needle adapted to be reciprocated transversely across said body in a substantially horizontal plane, a drive shaft, spur wheels operatively associated with said shaft, a bell crank connected at one end to said needle and at its opposite extremity secured to one of said spur wheels, loop-taking mechanism co-operating with said needle and operatively connected to said driving shaft, means for manually regulating the amount of penetration of the needle into the material comprising a plunger, a rocking bar connected to one end of said plunger and its opposite end secured to said drive shaft, manual means connected to said plunger for

adjusting the latter, a feeder, an oscillating link connecting said feeder to the drive shaft, a work plate, a box-like member below said plate, springs on said member resiliently supporting said plate, and means projecting from said member for raising or lowering the same. 5. The combination with the body of a chain-stitch sewing machine, of a needle adapted to be reciprocated transversely across said body in a substantially horizontal plane, a drive shaft, spur wheels operatively associated with said shaft, a bell crank connected at one end to said needle and at its opposite extremity secured to one of said spur wheels, loop-taking mechanism co-operating with said needle and operatively connected to said driving shaft, means for manually regulating the amount of penetration of the needle into the material comprising a plunger, a rocking bar connected to one end of said plunger, and its opposite end secured to said drive shaft, manual means connected to said plunger for adjusting the latter, a feeder, an oscillating link connecting said feeder to the drive shaft, a work plate having a raised portion for automatically imparting to the material the desired curve, a box-like member below said plate, springs on said member resiliently supporting said plate, and means projecting from said member for raising or lowering the same.

6. The combination with the body of a chain-stitch sewing machine, of a needle adapted to be reciprocated transversely across said body in a substantially horizontal plane, a drive shaft, spur wheels operatively associated with said shaft, a bell crank connected at one end to said needle and at its opposite extremity secured to one of said spur wheels, loop-taking mechanism co-operating with said needle and operatively connected to said driving shaft, means for manually regulating the amount of penetration of the needle into the material comprising a plunger, a rocking bar connected to one end of said plunger and its opposite end secured to said drive shaft, manual means connected to said plunger for adjusting the latter, a feeder, an oscillating link connecting said feeder to the drive shaft, a work plate having a raised portion for automatically imparting to the material the desired curve, a box-like member below said plate, springs on said member resiliently supporting said plate, and means projecting from said member for raising or lowering the same.

In testimony whereof I have hereunto set my hand.

ABRAHAM BELLOW.
